US00D722082S

(12) **United States Design Patent**
Roberts et al.

(10) **Patent No.:** **US D722,082 S**
(45) **Date of Patent:** **** Feb. 3, 2015**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Samuel Morgan Roberts**, Santa Cruz, CA (US); **Randall Ubillos**, Los Altos, CA (US)

(73) Assignee: **Apple Inc.**, Cupertino, CA (US)

(**) Term: **14 Years**

(21) Appl. No.: **29/495,818**

(22) Filed: **Jul. 3, 2014**

Related U.S. Application Data

(63) Continuation of application No. 29/415,042, filed on Mar. 7, 2012, now Pat. No. Des. 708,638.

(51) **LOC (10) Cl.** **14-04**

CLAIM

The ornamental design for a display screen or portion thereof with graphical user interface, as shown and described.

DESCRIPTION

The FIGURE is a front view of a display screen or portion thereof with graphical user interface showing our new design. The broken lines around the Figure show a display screen or portion thereof and form no part of the claimed design.

1 Claim, 1 Drawing Sheet
